EARLY VALUE SETTING MECHANISM

Harry F. Noller, Berkeley, and George K. Hurni, Oakland, Calif., and Kenneth F. Stone, Long Branch, N. J., assignors to Marchant Calculating Machine Company, a corporation of California

Application April 17, 1946, Serial No. 662,822

10 Claims. (Cl. 235—79)

The present invention relates to calculating machines which are capable of automatically performing multiplication and division calculations, and particularly consists of selection control mechanism which is operable immediately following initiation of a calculation, to maintain the actuator setting in the condition in which it was set under control of the depressed keys of the keyboard, to suspend the control of the keyboard over the actuator, and to clear the keyboard so that a factor of a new calculation may be set on the keyboard while the machine is still engaged in performing the previously initiated calculation.

This invention is disclosed as embodied in the commercially known Marchant calculating machine shown and described in the Avery Patent No. 2,271,240 and is shown as operable with the division mechanism of that machine, but the invention is applicable as well to multiplication mechanism or any other calculating mechanism in which the factor or factors of a calculation are set up on the keyboard and the calculation is initiated by depression of an initiating key.

Prior art calculating machines, such as that shown in the Dustin et al. Patent No. 2,377,767, have been provided with means for automatically clearing the divisor from the keyboard and selection mechanism as an incident to termination of a division operation, for example, so as to render the selection mechanism available for the introduction for new factors and thus save time, but automatic division operations frequently take such an amount of time, even in modern high-speed machines, that they interrupt an operator's continuity of work; that is, it is necessary for the operator to wait for the termination of a division operation before he can proceed with setting up a new factor.

The present machine on the other hand attains the objective of permitting the entry of a factor of a new calculation while the machine is engaged in performing the current calculation. This is done by establishing a connection between the keyboard and the actuator for setting the latter in accordance with the setting of the keyboard, locking the actuator in the condition in which it is thus set, and then disconnecting the keyboard from the actuator and clearing the keyboard to permit of setting a new factor therein without altering the previous setting of the actuator.

It is, therefore, a primary object of the present invention to retain the setting of a factor in a calculating machine throughout the operation

thereof and at the same time to render the selection keyboard available for setting up a factor of a new calculation while the machine is still engaged in performing a previously initiated calculation.

It is a further object of the invention to automatically clear the keyboard upon initiation of a calculation operation without interfering with the normal course of the machine calculation.

It is a still further object of the invention to provide means independent of the selection mechanism for locking the actuating mechanism in set condition upon initiation of a division operation so that changes in the selection setting, whether accidental or intentional, are unable to interfere with the division operation.

An additional object of the present invention is to suspend the effect of any keyboard setting upon the actuator mechanism of a calculating machine for the duration of a current division calculation, and to automatically render such a keyboard setting effective to set the actuator mechanism as an incident to initiation of a new calculating operation.

It is a specific object of the present invention to lock the actuator mechanism of a calculating machine in the set position established by the setting of its selection mechanism for the duration of an initiated division operation, while automatically clearing the selection mechanism upon initiation of said operation.

It is another specific object of the present invention to suspend the effect, upon the actuator mechanism, of any new selection setting, for the duration of an initiated division operation, and to automatically render such new selection setting effective to set the actuator mechanism upon initiation of a new calculation.

Other objects of the present invention will be apparent from the following detailed description of a preferred form of the invention, reference being had to the accompanying drawings forming a part of this specification, in which:

Figure 1 is a sectional elevation as viewed from the right illustrating the manual and power set selection mechanism and the control mechanism therefor and general arrangement of this mechanism in the machine embodying the present invention.

Figure 2 is a detailed view of a control cam operated by the setting clutch and employed in transferring a keyboard selection to the actuator mechanism.

Figure 3 is a detailed view of part of the selection mechanism shown in Figure 1.

Figure 4 is a right side view of the auxiliary clutch and the mechanism responsive to depression of the division key for controlling the clutch.

Figure 5 is a right side view of the selection locking mechanism and related control mechanism therefor.

Figure 6 is a right side view of part of the division mechanism of the machine embodying the present invention for comparing the divisor with the dividend or remainder and controlling the disengagement of the main clutch.

Figure 7 is a right side view illustrating the carriage dipping and rise controlling mechanism.

Figure 8 is a plan view of the setting and auxiliary clutches and the cams driven by each.

Figure 9 is a right side view illustrating the mechanism for automatically clearing the keyboard upon initiation of a division operation.

Figure 10 is a right side view of the setting clutch and part of the mechanism for controlling the same.

Figure 11 is a right side view of the main clutch and the mechanism for causing engagement and disengagement thereof.

Manual selection mechanism

The machine embodying the present invention includes a keyboard which is adapted to receive the entry of dividend and divisor factors, multiplicand factors, and items of addition and subtraction calculations. This keyboard is composed of numeral keys 100 (Fig. 1) which are arranged in a series of parallel banks or denominational orders consisting of ten numeral keys in each order to represent the numeral values zero to nine respectively. Each bank of keys is supported by a channel shaped frame 101 through which the key stems 103 of the various numeral keys are slidably mounted.

A compression spring 102 is provided for each key to normally maintain the same in raised position. All of the key stems 103 are of the same length, and each has a cam extrusion 116 which upon depression of the associated key cams a slotted key locking slide 117 toward the right as viewed in Figure 1. This locking slide is supported for sliding movement on the lower side of channel frame 101 by studs mounted on the frame. When a numeral key stem has been depressed the cam extrusion 116 passes beneath the slide and permits the same to return to its initial position under urge of spring 118, and by overlying the upper end of the extrusion 116, latches the depressed key in its depressed position. The setting of any value in a keyboard order or bank can be changed simply by depressing a different key in the same order. The depression of the second key cams the locking slide toward the right as described above and thus releases the key which was previously depressed and latched down.

Disposed beneath the numeral keys 100 in each bank is a differentially settable selection bar 120, which is suspended from channel frame 101 by means of two parallel links 128 and 129, freely pivoted on studs in the frame 101, thus permitting endwise movement of the selection bar 120. This bar 120 has nine identical V-shaped notches 130, each of which terminates in a slot 131 proportioned to receive the end of an associated key stem 103 so that the bar 120 will be accurately positioned. The key stems 103 are spaced equal distances apart, and these distances are slightly greater than the spacing between successive slots 131, so that each succeeding slot 131 will be spaced one increment further away from its co-

operating key stem. Depression of a numeral key will therefore cam selection bar 120 to the right a number of increments equal to the value represented by the depressed key.

The right end of selection bar 120 lies adjacent a stud 163 (Fig. 3), mounted on a depending arm 134 of a segment lever 132 which is pivotally mounted on a transverse shaft 137. The upper end of lever 132 is provided with a gear segment 138 which meshes with a pinion gear 145 mounted for rotation with a check dial 140 on a stationary transverse shaft 141.

A torsion spring 142 (Fig. 1) is wound around the shaft 141, with one end of the spring connected to the frame of the machine and the other to a stud 143 on the check dial so as to urge the dial in a counterclockwise direction about shaft 141. A zero stop 135, mounted on the frame of the machine, blocks such spring urged counterclockwise movement of the dial so that when none of the keys in a bank is depressed the dial is rotated to its zero position by spring 142 and blocked in such position by the zero stop, and in so doing returns the gear segment lever 132 to the normal position shown. Upon return of the segment the stud 163 thereof engages the end of the selection bar and returns the latter to the position shown. When, however, a numeral key is depressed and latched down as described above, the check dial 140 is rotated to and maintained in the position indicative of the value of the key depressed.

Power drive mechanism

The machine embodying the present invention derives its power from an electric motor and this motive power is transmitted to the various mechanisms within the machine by three independently operable clutches and mechanism driven by each. The first of these clutches is termed the setting clutch, sometimes referred to as a program clutch, which is operable in response to depression of a calculation initiating key to condition the machine for operation and control the sequence of certain of the calculation operations. The second clutch is termed the main clutch and drives the machine during the calculation operation, while the third clutch is termed the restore clutch and is operable following operation of the main clutch to restore the machine to a normal condition of rest. A fourth auxiliary clutch which constitutes a part of a novel mechanism of this invention will be described later.

Differential actuator

The numeral wheels of the accumulator register are driven by motive power through the main clutch mentioned above and what is termed a "continuous gear" actuator shown and described in the Avery Patent No. 2,271,240. The gears of this actuator are shifted to change the speed ratio in accordance with a given selection by a power set selection mechanism which is operable under control of a series of cams comprising a selection cam unit 146 (Fig. 1) for each row of keys. These cam units are set by the keyboard of the machine disclosed in the last mentioned patent and their setting corresponds at all times to the value of the key depressed in the related keyboard order and also to the same value shown on the check dial for that order.

According to the present invention, however, the check dials are not directly connected to the associated selection cam units but instead the cam units and check dials are each set independ-

ently of the other so that the cam units can be set in accordance with one value to control the operation of the machine while the check dials can be set by the keyboard in accordance with a different value such as the value of a factor of the next calculation without effecting the operation of the machine. This independent setting of the selection cams is accomplished by the following mechanism:

Power selection mechanism

A second selection segment lever 133 (Fig. 1) is freely pivoted on the shaft 137 in each order and is rockable independently of the first selection segment 132 described above. A gear segment 139 is provided on the lower end of lever 133 and meshes with a gear 151 forming part of the selection cam unit 146 mentioned above.

The segments and cam units are set in accordance with the value set on the keyboard by power operated mechanism driven by the setting clutch as follows:

Selection bar 120 possesses a depending extension 121 which is provided with a lateral stud 122. A link 180 is connected at its right end to segment lever 133 by a stud 181, while its free end is provided with a V-shaped notch 182 which is positioned approximately underneath the above mentioned stud 122 and has a central recess adapted to receive said stud. The free end of link 180 rests upon a transverse rod 183 supported by a plurality of arms 184 which are secured to a transverse shaft 190 suitably journaled in the frame of the machine. The upper end of a lever 185 is also pinned to this shaft 190 and the lower end is connected to the left end of a link 186. The right end of the latter link is pivoted to the lower end of a cam follower 187 (Fig. 2) which cooperates with a cam 188 which is keyed on a sleeve 431a journaled on setting clutch shaft 431.

After the setting of the aforementioned manual selection mechanism has been completed and upon depression of one of the operation control keys of the machine such as division key 970 (Fig. 4), the setting clutch 430 (Fig. 10) is engaged as will be described hereinafter, and power derived from the motor (not shown) is transmitted to setting clutch shaft 431 and its sleeve 431a. Consequent rotation of cam 188 (Fig. 2) pulls link 186 toward the right and rocks supporting shaft 183 (Fig. 1) upwardly, pressing V-notch 182 of selection link 180 against stud 122 on selection bar 120, which positions said link to correspond with the value of whatever numeral key 100 may have been depressed. Link 180 in turn positions lower segment lever 133 accordingly, thus setting selection cam unit 146 to represent the value selected by depression of a key. Upon further rotation of cam 188 beyond its lobe 188a, selection link 180 will return to its initial position under the influence of a spring 191, disengaging stud 122 of selection bar 120. By this time means, provided in accordance with the present invention, become operative to maintain selection cam unit 146 in the position of adjustment established by the above cam 188, as will be described herein-after.

Power setting of actuator

As soon as the cam units 146 are set in accordance with the manual setting of the keyboard, power operated mechanism is brought into play to sense the setting of the cam units and to shift the gears of the actuator so that the latter will

transmit to the accumulator register increments of movement which are proportional to the value originally set on the keyboard.

Each such cam unit comprises the previously mentioned gear 151 and five cams, one of which is shown in Fig. 1 and identified as cam 152. Each one of the cams has two high points 160 and two low points 161 on its periphery, the cams being so staggered that no high or low point on one cam is aligned with a high or low point on another cam. The various cams of cam unit 146 are so arranged that with a numeral key depressed, movement of segment 139 in response to operation of link 180 will rotate the cam unit 146 to a position in which one of the high points of one of the cams will be located in the path of a finger 211 of one of a set of five feeler arms 210 on one side of the cam unit 146 or in the path of a finger 219 of one of another set of five feeler arms 217 on the opposite side of the unit 146.

Keyed on the above mentioned setting shaft sleeve 431a is also a pair of complementary cams 220 and 221 (Fig. 1) and an associated cam follower 224, freely pivoted on a cross rod 225 and provided with a roller 222 in engagement with cam 220 and a second roller 223 in engagement with cam 221. As the cams rotate, the cam follower 224 is rocked counterclockwise early in the cycle to retract the feeler fingers 211 and 219 from the selection cam units 146 to permit the setting of the latter by the "Power selection mechanism" described hereinbefore. After the selection cams are so set, the cams 220 and 221 rock the cam follower 224 in a clockwise direction which then moves the feeler fingers 211 and 219 against the peripheries of their corresponding cams at points substantially diametrically opposite one another by mechanism disclosed in said Avery Patent No. 2,271,240.

As pointed out hereinbefore each of the cam units 146 is so designed that only one of the associated pairs of fingers is in engagement with the high or low point of a cam at any one setting of the numeral keys 100 in the respective denominational order of the keyboard. Thus, one of the feeler arms 210 in each order will be rocked at a considerable angle about its supporting shaft 213 to one side or the other of a medial position depending on whether its finger 211 is in engagement with a high point 160 or low point 161 of its corresponding cam while all of the other feeler arms in that order will be held in a medial position. Cams 220 and 221 make one half a revolution during the cycle, after which the opposite lobes of the cams come to the positions shown in Fig. 1 and retain the feeler fingers against the cam units throughout the remainder of the division operation and thus act to maintain the selection cam units in the position in which they were set by the power selection mechanism. Segments 133 will likewise be held in set position which is essential to the proper performance of a division operation because it is the position of these segments that ultimately determines the characteristic position of the sensing shelves 900 (Fig. 6).

Each of the feeler arms 210 is connected through a stud and slot connection 206 with one of five selection plates such as plate 172 which is rotatable about a transverse shaft 170. Plate 172 carries a set of gears 173 and 174, the latter meshing with a laminated gear 189 mounted on a keyed bushing 169. From the above it will be seen that four of each group of five selection plates will be held in their medial positions while the

fifth will be moved forward or rearward until the lowermost gear 173 thereon meshes with an aligned gear 175 on a shaft 166 or an aligned gear 176 on a shaft 167, said gears and shafts comprising the actuator unit of the machine disclosed in the Avery Patent No. 2,271,240.

Gear 175 is one of a group of four gears keyed on shaft 166 in each order and adapted to enmesh with the aligned gears on respective ones of the selection plates upon movement of the latter toward the left. Similarly, gear 176 is one of a group of five gears mounted on shaft 167 in each order and adapted to enmesh with aligned gears on respective ones of the five selection plates upon movement of the same toward the right.

The shafts 166, 167, and also a third shaft 168 are connected to a cyclically operable main clutch 428 (Fig. 11) through gear trains disclosed in detail in the aforementioned Avery Patent No. 2,271,240, the arrangement being such that shaft 166 (Fig. 1) otherwise known as the half-turn shaft rotates through 180 degrees for each cycle of operation of clutch 428 and shaft 167 (quarter-turn shaft) rotates through 90 degrees for each cycle of said clutch while shaft 168 (twelfth-turn shaft) moves through only 30 degrees for each cycle thereof. For the purpose of the instant description and its relation to the present invention, it is sufficient to understand that the various gears in each order of the actuator are shifted in and out of mesh with the gears on the half, quarter, and twelfth-turn shafts, so that for each main clutch cycle the gear 189 in a given order will be rotated a number of increments corresponding to the value of whatever numeral key 100 determined the setting of the selection plates in the particular order.

Selection locking mechanism

Means are provided for locking the selection plates 172 in any one of their three positions; said means comprises a locking bail 236 (Fig. 1) which extends across all orders of the actuator-selection unit and is pivoted at 237. This bail is connected by means of a link 528 to a cam follower 529 (Fig. 5) having rollers 530 and 531 which engage two respective complementary cams 526 and 527 secured to the above mentioned setting sleeve 431a. During the setting clutch operation described in the aforementioned Avery patent these cams are rotated through an angle of 180 degrees and in the first part of the operating cycle, they rock the locking bail downwardly so the selection plates 172 and their gears may be shifted, and then during the latter part of the cycle, they rock the bail up again to lock the plates in the position to which they were shifted by the power setting mechanism which operates during the middle of the setting clutch cycle.

Automatic keyboard clearing mechanism

After the foregoing mechanisms have operated to set and lock the selection cam units and the actuator selection plates in accordance with the factor set on the keyboard, the latter is cleared to enable the setting of a new factor thereon during the process of division. The keyboard is cleared as an incident to operation of the mechanism which causes engagement of the main clutch at the beginning of a division calculation as follows:

As described in the aforementioned Avery Patent No. 2,271,240, a cam 747 (Fig. 11), mounted on the setting shaft 431, rocks a cam follower 746 counterclockwise about a shaft 581. An in-

terponent 603 is mounted on the cam follower and when the latter is actuated by the cam, a shoulder 615 of the interponent engages a hook 616 on the main clutch dog 395 and rocks the same to clutch engaging position during the latter part of the first setting clutch cycle. A link 748 also described in the last mentioned patent is provided to actuate the keyboard clearing mechanism during addition and subtraction calculations. This link connects the cam follower 746 to a lever 750 (Fig. 11) fixed to one end of a shaft 752. The other end of this shaft carries a lever 774 (Fig. 9) which is adapted to engage an ear 776 formed on a link 779 when said link is lowered and the ear is positioned in the path of the lever 774. The link 779 is normally held in a raised position by a spring 783 but is lowered by depression of the plus or minus key of the machine disclosed in the last mentioned patent to cause actuation of the keyboard clear bail 125 which is freely pivoted on a shaft 126 and connected to the left end of link 779 at 781, said link being lowered during addition and subtraction operation by a link 811 also described in the same patent.

Means are provided in accordance with the present invention to also lower the link 779 upon depression of the division key as well as by the plus or minus key. This is accomplished by mounting an interponent 790 on the right end of link 779 by means of a stud 791 and enlarging the aperture 795 to permit the division key to lower the link without actuating the add and subtract key link 811. The interponent 790 is freely pivoted about the stud 791 and a spring 792 urges the interponent clockwise into the position shown where it lies under an ear 793 of the division key so that upon depression of said key the link will be rocked downwardly and the ear 776 positioned in the path of lever 774.

When the lever 774 is rocked by the linkage described above during the first setting clutch cycle and moves the link 779 toward the left to clear the keyboard, the interponent 790 slides from under the ear 793 of the division key and permits the spring 783 to raise the link 779. This moves the ear 776 above and out of the path of lever 774 so that subsequent rocking of the same during the repeated operation of the setting clutch in the current division calculation will not clear the keyboard again and destroy the setting of the factor of the next calculation.

When the division key rises at the end of division the ear 793 on the key stem will engage the side of the interponent 790 which had previously risen and the spring 792 will yield to permit the key to rock the interponent counterclockwise about the stud 791 as the ear 793 slides along the side of the interponent. When the key has fully risen the ear 793 will pass above the interponent whereupon the spring 792 will rock the latter clockwise to the position shown where it underlies the ear 793 and may be again engaged by the division key upon depression thereof for initiating the next calculation.

Automatic division mechanism

The sequence of operations involved in automatic division on machines of the type employed to illustrate the present invention is described in detail in the aforementioned Avery Patent No. 2,271,240 and will only be briefly outlined here. Depression of the division key 910 (Fig. 4) causes engagement of the setting clutch 430 (Fig. 10). This clutch drives a plurality of setting cams which affect various operations, some of which

were described hereinbefore, to condition the machine for the actual division operation. These operations include the following: (1) unlocking of the previously mentioned actuator plates 172 by retraction of locking bail 236; (2) sensing of the position of the selection cam units 146 by feeler arms 210 and 217 and setting of the actuator plate 172 accordingly; (3) returning bail 236 to locking position; (4) dipping of the carriage to enmesh the register drive gears 271 (Fig. 1) in each order of the register with the respective actuator gears 189; (5) adjusting the main reverse unit between the main clutch and the actuator shafts for negative operation; and (6) initiating operation of the main clutch.

In addition to these operations, the setting clutch causes specific division mechanisms to move into operative positions such as a division bail 907 (Fig. 6) and sensing shelves 900 which are normally withdrawn from operative positions for reasons which will be briefly referred to hereinafter. The first setting clutch cycle is followed by multicyclic operation of the main clutch which drives the actuator at such speeds as to subtract the divisor from the dividend once during each cycle of the main clutch.

Operation of the main clutch in a particular order is automatically stopped as soon as the effective dividend is reduced to a value below that of the divisor, the procedure being briefly as follows: The decreasing value of each digit of the effective dividend or remainder is represented by the position of a cam follower finger 1040 (Fig. 6) which is lowered by cooperation with a cam 281 attached to the respective accumulator dial 279. The value of each digit of the divisor introduced into the machine is represented by the position of a pivot 902 on which is mounted sensing shelf 900. The position of pivot 902 is determined by the position of selection segment 133 which for this reason is held in set position for the duration of the division operation. One end of the above mentioned sensing shelf 900 cooperates with the feeler finger 1040, in the associated order, while the other end blocks spring-urged movement of a division control member, namely the previously mentioned division bail 907. As cam follower finger 1040 is lowered by rotating snail cam 281, it presses down against the sensing shelf 900 rocking the shelf clockwise about the pivot 902 until its blocking end 906 releases the division bail 907 which then is free to move clockwise under the influence of its spring 944. This movement operates a train of levers which releases a latch 632 (Fig. 11) from underneath the main clutch dog 395, thus bringing about termination of the main clutch operation. This in turn initiates operation of the restore clutch 790 (Fig. 7) by a mechanism described in detail in the repeatedly mentioned Avery patent.

Operation of the restore clutch disables the latches 575 which retains the carriage in dipped position throughout the main clutch operation and at the same time operates cams 535 controlling the rate of return of the carriage to the position shown in Fig. 7 under the influence of a spring 569 and other springs in the carriage itself. The restore clutch also operates mechanism which determines whether an overdraft has occurred or not and then causes re-engagement of the setting clutch. Follows a second setting clutch cycle and depending upon whether an overdraft has occurred or not a second monocyclic operation of the main clutch may follow,

driving the actuators in positive direction to correct the overdraft. This cycle in turn is followed by a second restore clutch cycle in the particular order. In case that no overdraft has occurred, the arrangement is such that the second setting clutch cycle is directly followed by the above mentioned second restore clutch cycle. In both instances, this restore clutch cycle will operate to raise the carriage and initiate a single step carriage shift to the left which in turn conditions the machine to commence a new sequence of division operations in the new denominational order.

As described in the above mentioned Avery patent, movement of the carriage into its left-most position establishes conditions which enable the first subsequent restore clutch operation to unlatch the division key 970 and to enable the same to rise under influence of a spring 1801 (Fig. 4) and the linkage connecting the spring to the key. In its raised position the key establishes conditions that cause termination of the division operation in the particular order upon operation of the restore clutch through the subsequent cycle. Analogous conditions prevail whenever the division key is unlatched by depression of a stop key usually provided in machines of the type under discussion to terminate division in any order.

30 *Repeat operation and single operation setting cams*

Reverting to the setting clutch and cams of the machine embodying the present invention, it will be noted that the setting operations fall in two classes:

(1) Those which must occur repeatedly throughout a division calculation, such as that effected by the cam 574 (Fig. 7) for dipping the carriage following each ordinal shift, and by cam 747 (Fig. 11) for causing re-engagement of the main clutch, and others;

(2) Those which are necessary only at the beginning of each division calculation, such as the selection setting cams 220 and 221 (Fig. 1) for setting the actuator, and the actuator locking cams 526 and 527 (Fig. 5), and others.

Prior to this invention both classes of setting operations described above have been carried on together by repeated setting clutch operations described in the aforementioned Avery Patent No. 2,271,240. The present invention, however, provides means which will effect repeated setting operations of the first class but prevents such repeated operations of the second class during the successive operations of the setting clutch affected in the process of division, thereby considerably reducing the noise, wear, and operating load of the machine.

60 This is accomplished by mounting the cams which may be called single operation setting cams, on the sleeve 431a mentioned hereinbefore, and mounting the cams which may be called repeat operation setting cams on the setting clutch shaft 431, and by providing an auxiliary clutch which drives the sleeve 431a and its cams. The auxiliary clutch normally couples the setting shaft to the sleeve so that during the first operation of the setting clutch, both the single operation and the repeat operation cams are driven together and condition the machine for a calculation operation. If this operation is initiated by the division key, the latter causes disengagement of the auxiliary clutch at the end of its first cycle so that during the subsequent repeated

operations of the setting clutch and its cams, the single operation cams will be stationary.

According to the present invention the various cams described above, as being mounted on the sleeve 431a and driven by the auxiliary clutch, are of such shape and arranged in such timed relation to each other that upon rotation of the auxiliary clutch during the first setting clutch cycle the cams perform their respective functions in the following sequence:

(1) Complementary cams 526 and 527 (Fig. 5) retract the locking bail 236 (Fig. 1).

(2) Complementary cams 220 and 221 retract the feeler fingers 211 and 219 from engagement with the selection cam units 146 to permit the setting of the latter.

(3) Cam 188 (Fig. 2) actuates link 180 (Fig. 1) and sets the selection cam units 146 in each order.

(4) Cams 220 and 221 then return the feeler fingers to sensing position and set the actuator accordingly.

(5) Cams 525 and 527 return the locking bail 236 to the position shown in Fig. 1, thereby locking the actuator selection plates in the positions to which they were set by cams 220, 221, item (4) above.

The cams which are secured to the setting clutch shaft 431 and operate at successive stages of the division operation, include:

(1) Cam 574 (Fig. 7) which dips the carriage to enmesh the register gears 271 with the actuator gears 189.

(2) Cam 747 (Fig. 11) causes engagement of the main clutch 428.

In addition to the above described repeat operation cams, the Marchant calculating machine includes other cams with which we are not concerned, such as cams which are driven by the setting clutch for setting the main reverse unit and enabling certain division mechanisms. Since the latter cams and the operations which they affect are not altered by the present invention they are not shown or described herein but may be seen upon reference to the aforementioned Avery Patent No. 2,271,240.

The Marchant calculating machine, in which the present invention is embodied, has a multiplication mechanism of what is known as the "instantaneous" type which starts immediately upon depression of a multiplier numeral key. The machine has no way of knowing if the key depressed represents the first, last, or intermediate digit of the multiplier factor and consequently all setting operations must occur each time. As stated in the introduction of this specification, the present invention is applicable to multiplication as well as to division. It may now be more clearly seen that the invention is so applicable to multiplication if the machine includes what is known as the "delayed" type of multiplication mechanism wherein the multiplier digits are set up in a storage device and the multiplication operations are initiated by a multiplication or start key. This key could then function as does the division key in the present invention and retain the setting of the multiplicand in the actuator mechanism throughout the multi-digit multiplication calculation. As in the present invention, the keyboard could also be cleared to permit setting of a new multiplicand therein.

Auxiliary clutch

The auxiliary clutch 480 (Figs. 4 and 8) de-

scribed only generally hereinbefore includes a clutch disc 481 which is integral with the sleeve 431a and a clutch ratchet 482 which is integral with the setting shaft 431. This clutch is a half-revolution clutch and therefore includes two pawls 483 and 484 (Fig. 4) pivotally mounted on studs 485 and 486 respectively, carried on the clutch disc 481. Each pawl is spring-urged into engagement with one of two teeth of the ratchet 482 so that normally the disc, sleeve and its single operation cams are driven by and with the setting clutch shaft and its ratchet 482.

A clutch control dog 487 (Fig. 4) is held away from the auxiliary clutch when the machine is in the normal condition of rest so that the clutch will be in the engaged condition shown and, therefore, rotate with the setting shaft during its initial operation. If the machine operation is initiated by the division key, the clutch control dog is released and rocked counterclockwise under the urge of a spring 487c until it is blocked by the periphery of the clutch disc 481. When the auxiliary clutch has nearly completed its cycle (a half revolution), the nose of one of the pawls 483 or 484 is blocked by the ear 487a and rocked out of engagement with the tooth of the ratchet 482. At the same time, the tail of this dog engages the nose of the other dog, thereby rocking the latter out of engagement with the second tooth of the ratchet, and thus causing complete disengagement of the clutch. The clutch is held in this disengaged condition until the division key rises at the end of a division calculation, whereupon the clutch control dog is rocked outwardly to the position shown to permit re-engagement of the auxiliary clutch preparatory to the next calculation.

Auxiliary clutch control mechanism

As stated briefly hereinbefore, the single operation cams are normally coupled to the setting clutch shaft by the auxiliary clutch and operate with the setting clutch during multiplication by each multiplier digit. They also operate in this way in addition and subtraction and during the first setting clutch cycle in division calculation, but are disabled by disengagement of the auxiliary clutch during all subsequent setting clutch operations in division for the reasons set forth hereinbefore. This clutch disengagement is brought about by depression of the division key which adjusts certain mechanisms as follows:

The division key 970 (Fig. 4) is mounted on two parallel links 972 and 973, the latter of which includes an ear 980 which is moved upwardly and toward the left when the division key is depressed and is held in such position by a latch 982 thereby maintaining the division key in depressed position throughout the division calculation. A link 965 connects a downwardly extending arm of link 973 to a bell crank 1026 secured to shaft 1256 which is rocked clockwise upon depression of the division key through the above described linkage. A link 1476 connects the bell crank 1026 to a shift control link 1483 by means of a pin and slot connection 1483a. A lever 1736 is pivoted on a stationary stud 1736c and includes a shelf 1736b which underlies the stud 1483a. As described in the aforementioned Avery Patent No. 2,271,240, the link 1483 is lowered by the above described mechanism so as to disable the manual shift control mechanism which includes the link 1483. When the stud 1483a is lowered it depresses the shelf 1736b and rocks the lever 1736 downwardly or clockwise about its pivot

1736c and in so doing moves a stud 1736a, mounted on the right end of lever 1736, downwardly and from beneath a nose 487b of the aforementioned auxiliary clutch control dog 487 to permit the latter to rock to clutch disengaging position described above.

The depression of the division key also moves a link 514 (Fig. 10) downwardly by mechanism described in the last mentioned Avery patent, and rocks the setting clutch control dog 394 counterclockwise to cause engagement of the setting clutch 430 which drives the auxiliary clutch 480 (Fig. 4) through a half revolution after which the latter clutch is disengaged as described under the section heading "Auxiliary clutch." Since the division key is held down throughout the entire division calculation, the auxiliary clutch control dog 487 remains in its clutch disengaging position so that subsequent operations of the setting clutch are ineffective to drive the auxiliary clutch and its single operation cams.

As described in detail in the aforementioned Avery patent, the division key latch 982 is released during the first restore clutch cycle in the terminating order of a division calculation. The division key is retained in its depressed position, however, by mechanism described below, thereby preventing re-engagement of the auxiliary clutch and consequent operation of the same during what is known as the "second setting clutch cycle" in the terminating order of division. It is necessary to prevent such operation of the auxiliary clutch so as to prevent resetting of the actuator in accordance with the new factor set upon the keyboard if such setting has been made during the division calculation. This prevention is necessary to avoid an erroneous result in case an over-draft has occurred in the last order, which would require a final corrective main clutch cycle following the second setting clutch cycle.

As previously explained, division key 970 is operatively connected to a shaft 1256 so that upon depression of the key the shaft 1256 is rocked clockwise as viewed in Fig. 4 against the force of a restore spring 1801 connected between the machine frame and an ear on lever 1804 secured to shaft 1256. To delay restoration of the division key after release of latch 982 during the first restore clutch cycle in the terminating order of division, a member 1722 (Fig. 7) is provided, the upper fork of which has a tooth 1729 adapted to engage an ear 1802 of lever 1804 and to control the latter in a manner described in detail in Boyden Patent No. 2,393,018 dated January 15, 1946, to which reference may be had for a detailed description of the mechanism not specifically described herein. Member 1722 is pivotally mounted on a link 1713 by means of a stud 1723 and is provided with a spring 1725 tensioned between a tail of the member and a machine frame stud so as to constrain member 1722 to rock counterclockwise about its pivot 1723. The lower end of link 1713 is pivotally connected, by a stud 1724, to an arm 1725 pivotally mounted on the frame of the machine at 1728, while the upper end of link 1713 is pivotally connected to an arm 1714 fixed to a shaft 699 which is rocked counterclockwise by the carriage dipping mechanism during each setting clutch cycle and clockwise during each restore clutch cycle as described in detail in the aforementioned Avery Patent No. 2,271,240. The latching tooth 1729 (Fig. 7) is so positioned that when the division key 970 is held in depressed position by latch 982, ear 1802 stands to the right of tooth 1729. When latch 982 is

released a limited amount of upward movement of key 970 is permitted to prevent re-engagement of latch 982, but latching tooth 1729 prevents any appreciable counterclockwise movement of lever 1804 so that link 1736 (Fig. 4) is unable to rise sufficiently to cause re-engagement of the auxiliary clutch.

As the carriage is dipped during the middle part of the second setting clutch cycle by operation of the setting cam 574 (Fig. 7) the link 1713 and member 1722 are moved toward the left as viewed in Fig. 7 thereby permitting the lever 1804 and shaft 1256 to gradually rock counterclockwise under urge of the spring 1801 and thus cause the division key to rise. Near the end of the leftward movement of link 1722 a camming surface 1740 engages a frame stud 1740a which rocks the member 1722 upwardly to completely release the lever 1804 from restraint of the latching tooth 1729 so that the carriage may again rise during the last restore clutch cycle and the member 1722 may return to the position shown without engaging the ear 1802 and rocking lever 1804 with it.

The counterclockwise rocking of shaft 1256 described above moves the links 1476 and 1483 (Fig. 4) upwardly and the consequent upward movement of stud 1483a carried by the latter link permits the spring 289 to pull the link 1736 upwardly and to rock the auxiliary clutch control dog to clutch engaging position shown. The clutch pawls 483 and 484 are then free to rock inwardly under spring pressure, and upon completion of the second and last setting clutch cycle in the terminating order of division, the teeth of the ratchet 482 come to a stop in the position shown, in engagement with the pawls 483 and 484 and in condition to drive the same and the auxiliary clutch cams upon initiation of the next calculation.

Summary

Calculating machines which are capable of performing calculations automatically include mechanisms for causing repeated operation both for conditioning the machine for calculation and for actually performing the calculations in the successive denominational orders. Some of the conditioning mechanisms must operate repeatedly but others need be operated only at the beginning of a multi-order calculation. The present invention described hereinbefore provides mechanism for effecting all necessary conditioning operations at the beginning of the calculation and then suspends operation of all such conditioning mechanism not needed throughout the rest of the calculation, but permits the operation of all those which are needed in or before the calculations in each denominational order.

Machines of the class described, enter or transfer the dividend from the keyboard to the accumulator in a well-known manner, after which the divisor is set up on the keyboard. Upon depression of a calculation initiating key this factor is transferred to or set in part of the calculation control mechanism by a power selection mechanism driven by a setting clutch and is retained therein to control the calculation operations of the machine. The actuator is set by a power setting mechanism also driven by the setting clutch in accordance with the value of the factor set on the keyboard and is thus effective to control the positive or negative entry of the selected numeral value into the accumulator. In division calculation, the divisor is constant

throughout the calculation and therefore when the division key is depressed to initiate the calculation, this key is effective, in the embodiment of the invention illustrated, to disconnect the setting clutch from the power selection and actuator setting mechanism and the locking mechanism, so that subsequent recurring operations of the setting clutch during the process of division will not unnecessarily and repeatedly operate these mechanisms. This disconnection is in the form of an auxiliary clutch which is normally engaged so as to transmit power from the setting clutch to the cam which operates the above mechanism, and which is disengaged at the end of the first setting clutch cycle so as to thereafter suspend operation of these mechanisms. After the selection and actuator mechanisms are set and locked, the keyboard is then automatically cleared and disconnected from the other mechanisms to permit the setting of a new factor on the keyboard without effecting the current calculation operations of the machine.

The division key is latched down throughout a division calculation and therefore the auxiliary clutch is held disengaged throughout that calculation. The division key latch may be tripped at any stage of the division calculation by depression of a stop key, provided in the machine embodying the present invention, whereupon the division key will be permitted to rise at the proper time by subsequent operation of an automatic division key releasing means, to thereby terminate the division upon completion of the operation in the current order; or, the latch is tripped automatically upon movement of the carriage into its extreme end position, whereupon the division key rises and stops the division mechanism upon completion of the operation in the last order.

When the division key rises either following depression of the stop key or following movement of the carriage into the end position, the auxiliary clutch control dog is moved to clutch engaging position and the auxiliary clutch becomes engaged at the end of the last setting clutch cycle. The machine thereafter comes to a stop without operation of the auxiliary clutch but the latter is in condition to transmit power from the setting clutch to the power selection mechanism and actuator setting and locking mechanisms during the first cycle of the setting clutch in the next calculation regardless of what kind of calculation it is.

We claim:

1. In a calculating machine having a register, an actuator therefor, and a keyboard settable to represent a selected numeral value, a cyclic clutch, power selection mechanism controlled by the keyboard and operated by the clutch to adjust the actuator in accordance with the setting of the keyboard, and a device driven by said clutch and having a locking phase of operation during which it locks the actuators in the position to which the same was adjusted by said power selection mechanism and having an unlocking phase of operation during which it unlocks said actuator; the combination of, a manually settable key for initiating a machine operation including recurring cycles of operation of said clutch, with means jointly responsive to said key upon setting thereof and to said clutch upon operation thereof through the first of said recurring cycles for suspending operation of the power selection mechanism and suspending operation of said device through its unlocking phase by said clutch during subsequent recurring cycles of operation thereof.

2. In a calculating machine having conditioning mechanism operable to condition the machine for calculation operations, and a cyclic clutch operable through recurring cycles of operation during the calculation operations; the combination of, an auxiliary clutch operable upon engagement thereof to enable operation of the conditioning mechanism by said cyclic clutch and effective upon disengagement thereof to suspend operation of the conditioning mechanism by the cyclic clutch, a manually adjustable key for initiating a machine operation including said recurring cyclic operation of the cyclic clutch, and a device responsive to adjustment of the key for disengaging said auxiliary clutch upon operation of the cyclic clutch through the first of its recurring cycles of operation, with a device operable to terminate the operation of the machine, and means responsive to operation of said terminating device for causing re-engagement of said auxiliary clutch during the last of said recurring cycles of operation of the cyclic clutch.

3. In a calculating machine having a register, a differential actuator therefor, a factor receiving device adjustable in accordance with the numeral value of a factor received, and setting means operable to set the actuator in accordance with the adjustment of said receiving device; the combination of a cyclic clutch for operating said setting means as aforesaid, means for suspending operation of the setting means by said clutch, a manually adjustable key for initiating a machine operation including recurring cycles of operation of said cyclic clutch, and means responsive to adjustment of said key and operable during the first of said recurring cycles of said clutch for causing operation of said suspending means, with a device operable to terminate said machine operation, and means responsive to said terminating device and operable during the last of said recurring cycles of the clutch to disable said suspending means.

4. In a calculating machine having selection mechanism settable to represent various numeral values, a register, motor drive means, differential actuators controlled by the selection mechanism and operable by the motor drive means to actuate said register, and a program clutch intermittently operable through recurring cycles to cause recurring operations of the actuators during a plural order calculation; the combination of, a normally engaged auxiliary clutch operable by and with the program clutch and capable of disengagement to suspend operation of the auxiliary clutch with the program clutch during certain of said recurring cycles of the latter, a key for initiating operation of the program clutch, and means controlled by said key for disengaging the auxiliary clutch during the first of said recurring cycles of the program clutch, with control mechanism for the actuators including a two phase device driven by the auxiliary clutch and operable in the first phase of said device to connect the actuators to the selection mechanism to cause the latter to adjust the actuators and operable in the second phase of said device to disconnect the actuators from the selection mechanism.

5. In a calculating machine having selection mechanism settable to represent various numeral values, a register, motor drive means, differential actuators controlled by the selection mechanism and operable by the motor drive means to actuate said register, and a program clutch intermittently operable through recurring cycles to cause

recurring operations of the actuators during a plural order calculation; the combination of, a normally engaged auxiliary clutch cyclically operable by and with the program clutch and capable of disengagement to suspend operation of the auxiliary clutch with the program clutch during certain of the recurring cycles of the latter, control mechanism for the actuators including a cyclically operable device driven through two phases of each cycle thereof by the auxiliary clutch during a single cycle of the latter and operable in the first phase of a cycle to connect the actuators to the selection mechanism to cause the latter to adjust the actuators and operable in the second phase of the same cycle to disconnect the actuators from the selection mechanism, a key for initiating operation of the program clutch, and means controlled by said key for disengaging the auxiliary clutch during the first of said recurring cycles of the program clutch.

6. In a motor driven calculating machine having selection mechanism settable to represent various numeral values, a register, selectively adjustable differential actuators therefor, a main clutch effective upon engagement thereof to drive the actuators, and a program clutch intermittently operable through recurring single cycles of operation to cause recurring engagement of the main clutch during a plural order calculation; a normally engaged auxiliary clutch which when so engaged is coupled to the program clutch and operable therewith and capable of disengagement to suspend operation of the auxiliary clutch during subsequent cycles of the program clutch, control mechanism for the actuators including a device driven through two phases of operation by the auxiliary clutch and operable in its first phase to connect the actuators to the selection mechanism to cause the latter to adjust the actuators and operable in its second phase to disconnect the actuators from the selection mechanism, a key for initiating operation of the program clutch, and means controlled by said key for disengaging the auxiliary clutch at the end of the first of said recurring cycles of the program clutch to suspend operation of said device during subsequent cycles of the latter clutch.

7. In a motor driven calculating machine having selection mechanism settable to represent selected numeral values, a register, selectively adjustable differential actuators therefor, motor operated drive means for said actuators, a program clutch intermittently operable through recurring cycles to cause recurring operations of the actuator drive means during a plural order calculation, and a cyclically operable auxiliary clutch; the combination of, actuator control means including a two phase device driven by the auxiliary clutch and operable during the first phase of said device to connect the actuators to the selection mechanism to cause the latter to adjust the actuators and operable in the second phase of said device to disconnect the actuators from the selection mechanism, means also driven by the auxiliary clutch and rendered effective to lock the actuators in adjusted condition after adjustment thereof by the selection mechanism and before disconnection of the actuators from the selection mechanism by said control means, numeral keys for resetting the selection mechanism, a key for initiating operation of the program and auxiliary clutches, and means controlled by the initiating key to cause disengagement of the auxiliary clutch at the end of its first cycle and prevent operation thereof during

the subsequent recurring cycles of the program clutch.

8. In a motor driven calculating machine having selection mechanism settable to represent selected numeral values, a register, selectively adjustable differential actuators therefor, motor operated drive means for said actuators, a program clutch intermittently operable through recurring cycles to cause recurring operations of the actuator drive means during a plural order calculation, and a cyclically operable auxiliary clutch; the combination of, actuator control means including a two phase device driven by the auxiliary clutch and operable during the first phase of said device to connect the actuators to the selection mechanism to cause the latter to adjust the actuators and operable in the second phase of said device to disconnect the actuators from the selection mechanism, means also driven by the auxiliary clutch and rendered effective to lock the actuators in adjusted condition after adjustment thereof by the selection mechanism and before disconnection of the actuators from the selection mechanism, numeral keys for resetting the selection mechanism, a key for initiating operation of the program and auxiliary clutches, and means controlled by the initiating key to cause disengagement of the auxiliary clutch at the end of its first cycle and thereby render the selection mechanism ineffective to change the adjustment of the actuators during the subsequent recurring cycles of the program clutch.

9. In a calculating machine having a keyboard settable to represent a selected numeral value, a register, an actuator selectively adjustable under control of said keyboard to actuate said register, and a cyclic clutch; the combination of, a device driven by said clutch and having a first phase of operation during which it connects the actuators to the keyboard to cause the latter to adjust the actuator and having a second phase of operation during which it disconnects the actuator from the keyboard, keyboard clearing mechanism, and a member driven by said clutch in such timed relation to said device as to cause operation of said clearing mechanism after operation of said device through its second phase, with a manually settable key for initiating a machine operation including recurring cycles of operation of said clutch, means jointly responsive to said key upon setting thereof and to said clutch upon operation thereof through the first of said recurring cycles to suspend operation of said device and said member by said clutch during subsequent recurring cycles of operation thereof.

10. In a calculating machine having selection mechanism, a register, calculating mechanism operable to control said register, cyclically operable motor drive means for said calculating mechanism, differentially settable control means comprising a part of said calculating mechanism for determining the number of cyclic operations of the motor drive means, a cyclic clutch for causing a plurality of recurring operations of said drive means during a plural order calculation, a device driven by said clutch and having a first phase during which it connects the differentially settable means to the selection mechanism to cause the latter to set the settable means and a second phase during which it disconnects the settable means from the selection mechanism; the combination of, a manually depressible key for initiating operation of the calculation mechanism including recurring cycles of operation of said clutch, with means controlled by said key and

responsive to said clutch upon operation thereof through the first of said recurring cycles for suspending operation of said device by said clutch during subsequent recurring cycles of operation thereof.
